UNITED STATES PATENT OFFICE.

GEORGE W. WARMOTH, OF INDIANAPOLIS, INDIANA.

COMPENSATING AND DRAINAGE JOINT FOR PAVEMENTS.

Application filed January 23, 1925. Serial No. 4,205.

This invention relates to a device for roads such as concrete roads and the like, wherein the same, due to expansion or other causes, cracks. These cracks permit moisture to seep therein and therethrough to the foundation or sub-grade and in time form a soft spot beneath the pavement or road by washing away a portion or all of the sub-grade.

10 The chief object of the present invention is to prevent the formation of the aforesaid soft spot and sub-grade washing and to prevent moisture expansion of the concrete by carrying away the water from the surface 15 to the sub-grade.

Another object of the invention is to construct the device in such a manner that it serves as a joint.

Another object of the invention is to construct the device in such a manner that it serves as an anchorage for anchoring the pavement to the sub-grade and thus prevents slipping of the surface with respect to the foundation and prevents slipping of 25 the foundation with respect to the sub-grade.

One feature of the invention in addition to the device accomplishing the foregoing objects is that it forms a joint in the pavement which will permit the pavement in its 30 expansion and contraction due to temperature changes, to crack at the joint.

The full nature of the invention will be understood from the accompanying drawings and the following description and claims:

In the drawings Fig. 1 is a longitudinal sectional view of a roadway showing the preferred form of the invention. Fig. 2 is 40 a transverse sectional view of a roadway showing the invention. Fig. 3 is a top plan view of the invention.

In the drawings 10 indicates the sub-grade and positioned upon the sub-grade is the bottom course 11, which may be of any suitable character for supporting the pavement or roadway 12, which may be of suitable material but which is generally of concrete.

The joint or sectionalizer includes a longitudinal member, herein illustrated in the form of a plate 13, having an inclined groove 14 formed therein which forms a channel or lead. The upper edge of the plate may be suitably formed as well as the lower edge, but herein the lower edge is

shown toothed as at 15. It is to be understood, (see Fig. 2), that the sectionalizer or joint extends from the pavement through the bottom course and is anchored by the teeth or other suitable anchorage means to the sub-grade. Thus the pavement is anchored to the bottom course and the bottom course to the sub-grade. When positioned, as shown in Fig. 2 the alternate expansions and contractions will form a crack 16, immediately above the joint or sectionalizer, since this is the thinnest portion of the pavement and will crack first. If desired the crack 16 may be formed in the pavement.

Howsoever the crack 16 is formed, the water, which collects on the pavement and passes through the crack, passes over the plate 13 until it passes into the inclined channel 14 or lead, whereupon it flows down the channel or lead to the bottom of the plate. If suitable means is provided at the discharge end of the channel or lead for receiving the before mentioned seepage the same will not wash away or soften the bottom course or the sub-grade immediately adjacent the same. Such a collection device includes a suitable water percolative material positioned in a well at the discharge end of the channel or lead.

Herein such material, which may be of gravel and the like, is indicated by the numeral 17. The well is indicated by the numeral 18 and may be formed by digging the same with a post hole device. As a further means of anchorage and to secure further rigidity and other desirable features, a thimble is provided. The thimble may be polygonal, circular, or of any desired outline. The thimble includes a body portion 19, the lower edge of which is provided with teeth 20 which constitutes the anchoring means or anchorage that is driven into the sub-grade, said thimble being positionable in the post hole 18. After thus positioning the thimble so that its upper edge 21 projects above the sub-grade, said thimble is filled with water percolative material, such as gravel and the like, and thereafter the joints or sectionalizer are associated therewith. The top 21 of the thimble is suitably notched as at 22.

As shown clearly in Figs. 1 and 2, the sectionalizer or joint member 13 is associated with the thimble so that converging channels or leads discharge into the thimble.

The device preferably is so constructed that the saw tooth or anchorage portions 15 interlock with the notches 22, and thus prevent longitudinal as well as transverse relative movement between the thimble and the joint.

As shown in the drawings, the channel or lead forming groove serves as a longitudinal reinforcement and also as a transverse reinforcement for the plate 13. Herein the 10 upwardly converging channels or leads communicate with each other adjacent the upper edge of the joint but not at the upper edge. They may communicate at the upper edge if desired, however. Furthermore, the joint 15 13 is provided with openings 23 that may serve as an anchorage for reinforcement when used in concrete roads. Other suitable means for anchoring the reinforcement to the longitudinal joint member may be utilized 20 as well. The joint members 13 may be constructed in individual units, each of which includes but a single inclined channel 14, or may be so constructed as to include a pair of converging or a pair of diverging channels, 25 or leads or may be so constructed as to include a plurality of converging and diverging channels or leads, the latter construction being shown in Figs. 1, 2 and 3, and being the commercial type of the invention.

As will be readily apparent from the drawings, it will be understood that the thimble may be positioned slightly off center, that is the center of the thimble may not exactly 35 coincide with the plane of the joint and the thimble may be so positioned that the roots of teeth 15 do not register with the notches 22, but may be slightly offset therefrom, and furthermore the thimble may not be medially positioned for registration with the converging channels or leads but may be offset 40 therefrom one or more teeth.

The invention claimed is:

1. A device for roads and the like comprising an elongated member including an inclined lead and a supporting thimble into which the elongated member lead is adapted 45 to discharge.

2. A device for roads and the like comprising an elongated member including an inclined lead, a supporting thimble into which the inclined lead discharges, and an inter-locking arrangement between said elongated member and said thimble for anchoring 50 the same against predetermined relative movement.

3. A device of the character described in claim 1 characterized by the addition of an-

chorage means upon the longitudinal member.

4. A device of the character described in claim 1 characterized by anchorage means upon the thimble.

5. A device of the character described in claim 1 characterized by anchorage means 65 upon the elongated member and the thimble.

6. A device of the character described in claim 1 characterized by anchorage means upon the elongated member and a complementary socket upon said thimble for association with one of the anchorage means for securing the thimble and the elongated member against predetermined relative movement.

7. A device for roads and the like comprising an elongated vertically positionable 75 member including a pair of downwardly inclined and converging leads discharging adjacent each other.

8. A device for roads and the like comprising an elongated vertically positionable 80 member including a pair of downwardly inclined and diverging leads discharging oppositely from each other.

9. A device for roads and the like, comprising an elongated vertically positionable 85 member including a plurality of downwardly inclined leads arranged in pairs, the leads of each pair having their lowest portions discharging adjacent each other and the two end leads being divergently inclined 90 with respect to the intermediate pairs of leads.

10. A roadway construction including a sub-grade, a bottom course, a pavement, and an elongated member including an inclined 95 lead, said member being positionable in said pavement, bottom course and sub-grade and extending through the bottom course, and a water permeable construction in said sub-grade into which said lead discharges.

11. A device as defined by claim 7, characterized by the addition of anchoring teeth on the lower portion of said elongated member.

12. A device as defined by claim 8, characterized by the addition of anchoring teeth on the lower portion of said elongated member.

13. A device as defined by claim 9, characterized by the addition of anchoring teeth 110 on the lower portion of said elongated member.

In witness whereof, I have hereunto affixed my signature.

GEORGE W. WARMOTH.
